UNITED STATES PATENT OFFICE.

FRANK DENNINGER, OF NEW YORK, N. Y.

WOOD-BENDING MACHINE.

SPECIFICATION forming part of Letters Patent No. 228,878, dated June 15, 1880.

Application filed April 5, 1880. (No model.)

To all whom it may concern:

Be it known that I, FRANK DENNINGER, of the city, county, and State of New York, have invented a new and useful Improvement 5 in Wood-Bending Machines or Presses for Bending and Veneering Piano-Forte Rims, of which the following is a specification.

The object of my invention is to construct a press for bending rims of piano-fortes to the shape required, and at the same time veneering the rims, by which press a number of the rims may be operated on at once.

My invention consists in a press-bed of rectangular form having combined with it loose 15 presser-blocks of the shape to which the rims are to be pressed, and fitted with clamping shackles and screws for compressing and holding the rims which are placed between the blocks in the press. The presser-blocks are 20 also fitted with adjustable gages for retaining the rims in position.

The improved press is shown in the accompanying drawings, wherein Figure 1 is a side elevation. Fig. 2 is a vertical section on line 25 *xx* of Fig. 1.

Similar letters of reference indicate corresponding parts.

A is the stand of the press supporting the bed, which consists of the short side portion, 30 *a*, and long side, *a'*, forming the rectangular bed. These side pieces, *a* *a'*, are tied by bolts *b*, and are fixed with the angle at the center of stand *A*.

Upon the stand *A* is fitted a shackle, *B*, 35 composed of a side bar, *c*, end bars, *d* *d*, and strap *e*, connecting the end bars, *d*. The upper end bar, *d*, is fitted with screws *h* *h*.

C are the presser blocks, made to the shape to which the rims are to be bent, and fitted with strips or gages *f* *f'* at their ends, which 40 retain the blocks *C* apart and prevent end movement of the rims. The strips *f* *f'* are adjustable on each block *C*, so as to be moved in or out, according to the length of the rim.

D *D* are shackles or clamps placed around 45 the side *a'* of the bed and the blocks *C*, and fitted with screws *g* for clamping those parts together.

In using this press the shackles *D* and the strap *e* of shackle *B* are first removed, and the 50 blocks *C* then put in place with the rims *i* between them. The strap *e* and shackles *D* are then applied and the screws *h* *g* turned to bring the blocks tightly together. By these means four or more rims may be pressed at 55 once and the same bend given to each.

The veneering will be applied to the rims immediately before they are placed in the press, and by the bending operation will be pressed 60 tightly to place.

Having thus described my invention, I claim as new and desire to secure by Letters Patent—

The combination, in a wood-bending machine, with the frame *A*, of the angular bed *a* 65 *a'*, the clamps *B* *D*, having screws *h* *g*, and the presser-blocks *C*, having gages *f* *f'*, for the special purpose set forth.

FRANK DENNINGER.
